[57] **CLAIM**

The ornamental design for a foot support for a lineman's climbing hook, as shown.

DESCRIPTION

FIG. 1, is a right side elevational view of a foot support for a lineman's climbing hook showing my new design. FIG. 2, is a side elevational view of the opposite side of the foot support.

FIG. 3, is a plan view of the foot support.

FIG. 4, is a bottom view of the foot support.

FIG. 5, is a front end elevational view of the foot support.

FIG. 6, is a rear end elevational view of the foot support.
